UNITED STATES PATENT OFFICE.

JAMES JESSEN, OF MILWAUKEE, WISCONSIN, ASSIGNOR, BY MESNE ASSIGNMENTS, TO INDUSTRIAL RESEARCH CORPORATION, OF TOLEDO, OHIO, A CORPORATION OF DELAWARE.

TRACTOR.

Application filed November 15, 1917, Serial No. 202,125. Renewed November 2, 1928.

The invention relates to tractors.

The invention is designed to provide an improved engine driven tractor of the type in which the operation of the driving mechanism and the steering mechanism is controlled by the use of lines or reins in the hands of the operator.

One object of the invention is to provide an improved line drive control.

10 A further object of the invention is to provide a simple and efficient mechanism for turning the tractor.

The invention is further designed to provide a new and improved form of tractor.

15 The invention further consists in the several features hereinafter described.

In the drawings:

Fig. 1 is a view of one side of the tractor; Fig. 2 is a plan view thereof;

20 Fig. 3 is a section taken on the line 3—3 of Fig. 1, parts being broken away;

Fig. 4 is a section taken on the line 4—4 of Fig. 3;

25 Fig. 5 is a section taken on the line 5—5 of Fig. 1;

Fig. 6 is a section taken on the line 6—6 of Fig. 5;

Fig. 7 is a section taken on the line 7—7 of Fig. 4;

Fig. 8 is a section taken on the line 8—8 of Fig. 4;

Fig. 9 is a detail plan view of the line control showing it in neutral position;

30 Fig. 10 is a detail plan view of the line control showing it in position for backward drive;

Fig. 11 is a detail plan view of the line control showing it in position for forward drive;

35 Fig. 12 is a detail side view of the locking catch for the line drive control for neutral position; and

Fig. 13 is a detail plan view of a portion of the line control.

40 In general, the tractor comprises a frame, driving mechanism mounted thereon, steering mechanism operated by the driving mechanism, and a line control for controlling the operation of the driving mechanism and steering mechanism.

The tractor frame consists of axles 14 carrying the tractor wheels 15, side frame members 16 to which the axles are secured, transverse frame members 17, 17', 17'' and 18, an

arc-shaped channel frame member 19 secured to the members 16 and 17', a king bolt 20 pivotally centrally mounted in the frame member 18, a king bolt coupling member 21 having arms 22 and 23 disposed above and below the member 18 and through which the bolt 20 extends, a rearwardly extending tubular frame member 24 secured at its forward end to the coupling 21 by a bolt 25, an adjustable yoke 26, adjustably secured by a bolt 26' to the frame and carrying axles 27, rear wheels 28 mounted on said axles 27, a seat support 29 mounted on the member 24 adjacent the rear wheels, and a seat 30 carried by said support 29, Fig. 1. If desired the rear wheels 28 may be removed and the member 24 secured to the tongue of a vehicle to be moved.

The driving mechanism comprises a motor 31, preferably an internal combustion engine, carried by the frame of the machine 75 and having a drive shaft 32 and transmission mechanism between said shaft 32 and the tractor wheels 15. The engine is preferably one which is governed in any suitable manner to run at substantially constant 80 speed. The engine is cooled by a radiator 33 suitably connected up in a well known manner to the engine, Fig. 2.

The transmission mechanism comprises a driven shaft 34, gearing connections between 85 said shaft and the tractor wheels, a shaft 35, a change speed gearing connection between said shaft 35 and the shaft 34, and a reversible driving connection between the shaft 35 and the drive shaft 32, Fig. 5. 90

The gearing connection between the shaft 34 and the wheels 15 comprises a gear 36 mounted on a shaft 34 and in mesh with an annular gear 37 carried by one of the wheels 15, and a differential gearing connection 95 between said shaft and the other wheel, Figs. 1 and 5. This differential gearing connection consists of bevel gears 39 meshing with the gear 36 and carried by a member 40, a bevel gear 41 loosely mounted on the shaft 34 and meshing with the gear 39, a sleeve 42 mounted on the shaft 34 and adapted to be secured to the gear 41 in any suitable manner as by a clutch device consisting of an interlocking connection 41' 100 between the gear 41 and sleeve 42, said sleeve carrying a gear 45 in mesh with an annular gear 37 carried by the other wheel 15, Fig. 105

5. To lock the differential a spring pressed key 42' is adapted to be inserted in the key way 34' in the shaft 34 when desired. With this construction the tractor wheels are 5 driven upon the rotation of shaft 34 and the differential permits the speed of rotation of the wheels to be varied with respect to each other so as to allow for turning corners. The change speed gearing connection 10 between the shaft 34 and the shaft 35 comprises a high speed gear 46 and a low speed gear 47 secured to the member 40, and gears 48 and 49 slidably mounted on the shaft 35 and adapted to mesh respectively with the 15 gears 47 and 46 or to be moved to neutral position, Fig. 5. Means are provided for shifting the gears 48 and 49 which will only be briefly mentioned here and for further detailed description of the same reference 20 may be had to my copending application, Serial Number 194,896 filed October 5, 1917. This gear shifting mechanism includes two members 50 and 51 slidably mounted on rods 52 and having portions 53 for engaging the 25 gears 48 and 49. These members 50 and 51 are moved to bring the gears 48 and 49 alternately into engagement with the gears 46 and 47 respectively by means of a rotatable shaft 54 and gearing connection between 30 said shaft and the members 50 and 51 consisting of toothed members 55 and 56 adapted to mesh with toothed projections 57 on the members 50 and 51 as will more fully appear in the above mentioned application. 35 Any suitable means may be used to turn the shaft 54 and secure it in different positions. With this construction the shaft 34 is driven at high or low speed or is disconnected.

40 The reversible driving connection between the drive shaft 32 and the shaft 35 comprises a sun gear 58 mounted on the shaft 32, an orbit gear 59 on the shaft 35 and a plurality of planetary gears 60 meshing with said sun and orbit gears and journaled on stud shafts 45 61 carried by a disk 62 revolvably mounted upon the shaft 32, Figs. 5 and 6. The disk 62 is yieldingly connected to a movable drum 63 by means of studs 64 secured to the disk 62 and passing through apertures in the 50 drum 63 and carrying coiled springs 65 which press against the sides of the drum, the disk being slidably mounted in an annular recess 66 in the drum 63. The drum 63 is provided with a conical face having a friction facing 67 which is adapted to contact with a drum 68 carried by the shaft 32 and having an annular conical clutch face 69 adapted to frictionally engage the facing 67 to form a frictional clutch. The drum 63 is adapted to be moved out of frictional engagement with the drum 68 by means of a crank or lever 70 secured to a shaft 71 journaled in the casing 72 and carrying arms 73 to which a yoke member 74 is pivotally connected, said yoke member engaging in an an-

nular recess 75 in the hub of the drum 63. With this construction the springs 65 normally hold the drum 63 in frictional engagement with the drum 68 but on a shifting of the crank 70, through the line control hereinafter described, the drum 63 will, through the movement of the shaft 71, arms 73 and 74, be moved out of frictional engagement with the drum 68 against the action of the springs 65. When this occurs no power will 75 be transmitted to the shaft 35.

Means are also provided for holding the drum against movement when it is moved out of engagement with the drum 68 comprising a brake band 76 provided with a 80 brake lining 76' and secured at one end to the casing 72 and at the other to a crank 76 mounted on a movable shaft 77, the movement of which is controlled by the line drive control hereinafter described, Figs. 5 and 6. 85 With this construction when the friction clutch is in, that is, when the drums 63 and 68 are in frictional engagement with each other, the disk 62 being non-rotatably secured to the drum 63 will be rotated with the shaft 32 and the drive for the shaft 35 will be locked through the gears 58, 59 and 60 to turn said shaft in the same direction as the shaft 32. This condition obtains for forward drive of the tractor. When the drums 63 and 68 are thrown out of engagement with each other the drive to the shaft 35 will be stopped. When the drums 63 and 68 are thrown out of engagement with each other and the drum 63 secured against rotation by the application of the brake in the manner previously described, then the disk 62 will also be held against rotation and the drive for the shaft 35 will be from the gear 58 through the idler gears 60 to the gear 59. 100 This condition obtains for backward drive of the tractor.

105 The steering mechanism comprises a segmental rack 78 secured to the tubular frame member 24 and to braces 79, a gear 80 meshing with said rack and mounted on a shaft 81 journaled in the casing 82, and means driven by the engine 31 for turning said shaft 81 in either direction.

110 This shaft turning means consists of a worm wheel 83 mounted on the shaft 81, a worm 84 meshing therewith and mounted on a shaft 85, a bevel gear 86 mounted on the shaft 85 and meshing with oppositely disposed bevel gears 87 and 88 mounted on a 115 shaft 89, means for connecting and disconnecting either of said gears 87 and 88 from driving engagement with the shaft 89, and a driving connection between the shaft 89 and the engine 31 consisting of a bevel gear 90 mounted on the engine shaft 32 and meshing with a bevel gear 91 on a shaft 92 which carries a bevel gear 93 meshing with a bevel gear 94 on the shaft 89, Figs. 3 and 4.

120 The means for connecting and disconnect-

ing the gears 87 and 88 with the shaft 89 comprises oppositely disposed friction clutches. Each of said clutches comprises a clutch disk 95 keyed to the shaft 89 and a clutch disk 96 keyed to but slidably mounted on its respective bevel gear, the disks 96 each having an annular groove 97 therein for receiving the bifurcated end 98 of a clutch shifting member 99 slidably mounted on a guide rod 100. The movement of this member 99 is controlled by the line drive control and by shifting this member both clutches may be disconnected or one clutch will be in when the other is out, Figs. 3 and 4. By means of this construction rotary motion is transmitted from the engine shaft 32 through the shafts 92, 89 and 85 to the shaft 81 to turn said shaft in the desired direction so that the parts of the frame pivotally connected to the king bolt 20 will swing or turn about said bolt in the desired direction, the gear 80 moving the rack 78 for this purpose. The rack 78 is held in proper alignment and guided by guide rollers 101 secured to brackets 102 carried by the rack and moving in the channel of the arc-shaped frame member 19, Figs. 1, 2 and 4.

The line control for the driving mechanism consists of line controlled means for operating the transmission clutch and the transmission brake band.

The line controlled means for operating the transmission clutch mechanism consists of a link 103 pivotally connected at one end to the crank 70 and at its other end to a bell crank lever 104 pivotally mounted on a pin 105, a cam roller 106 carried by said lever 104 and engaging a cam 107 mounted on a control shaft 108, and mechanism controlled by the lines for turning the shaft 108, Figs. 3, 5, 6, 7 to 12.

The line controlled means for operating the transmission brake band consists of a link 109 pivotally connected at one end to a crank 110 carried by the shaft 77 and pivotally connected at its other end to one end of a lever 111 which is pivotally mounted intermediate its ends on the pin 105 and carries a cam roller 112 at its other end engaging a cam 113 on the control drive shaft 108, Figs. 3, 5, 6, 7 to 12.

The mechanism controlled by the lines for turning the shaft 108 comprises an arm 114 secured to said shaft and a three arm lever 115 pivotally secured intermediate its ends by a bolt 116 to the free end of arm 114, the arms 117 and 118 of said lever having reins 119 and 120 respectively connected thereto. The shaft 108 is normally turned in one direction by a spring 121 secured at one end to the arm 114 and at the other by a bolt 122 to the frame member 17. The shaft 108 is adapted to be secured in neutral position by means of a latch 123 pivotally mounted inter-

mediate its ends upon the casing 82 and having a notch 124 therein for receiving the end of an arm 125 integral with the arm 114 but extending on the opposite side of the shaft 108. This latch 123 carries an adjustable weight 126 and an adjustable screw 127 limits its movement, Figs. 9 to 172 inclusive.

The line control for the steering mechanism consists of line controlled means for shifting the member 99. This consists of a segmental gear 128 meshing with toothed projections 129 on the member 99 and mounted upon a shaft 130, and line controlled means for turning this shaft, Figs. 3, 4, 7, 9 to 12.

The line controlled means for turning the shaft 130 consists of a segmental gear 131 carried thereby and meshing with a segmental gear 132 formed in a control member or lever 133 pivotally mounted intermediate its ends upon the shaft 108 and adapted to be moved by a link 134 pivotally connected at one end to the end 135 of the lever 133 and at its other to the end of the arm 136 of the lever 115. A spring 137 is secured at one end to the end 138 of the lever 133 and at its other to the frame member 17 to hold the lever 133 in normal position. The end 135 of the lever 133 and the arm 136 of the lever 115 are of equal length and the arm 114 and link 134 are of equal length and as these parts are pivotally connected with respect to each other, a parallelogram frame is formed, the position of the sides of which may be varied by moving the arm 114 through the pull on the lever 115 by the reins.

In operating this machine the engine is started by turning the shaft 92 by any suitable agency as by a starting crank 140 suitably connected up to said shaft. Then either the gear 49 is thrown into mesh with the gear 46 or the gear 48 into mesh with gear 47 on the turning of the shaft 54 in the proper direction, the selection of what speed is to be used depending upon the work to be performed by the tractor as for instance low speed is used for ploughing and high speed for hauling on the road. The machine is now ready for work and the operator from his place on seat 30 manipulates the reins in much the same manner as if he were driving a horse. When the parallelogram frame is in the position shown in Fig. 9, the parts are in neutral position and are secured in this position by the latch 123 engaging the arm 125 through the steering mechanism may be operated by pulling either of the reins 119 and 120 to turn the lever 115 which through the link 134, lever 133, gears 132 and 131, gears 128 and 129 will shift the member 99 so as to throw in the proper clutch to drive the shaft 85 and through the gearing connection previously described to turn the tractor from about the king bolt

20 in the desired direction. If the tractor is to be driven forward, with the parts in neutral, the operator pulls back on the reins 119 and 120 and then lets them move forward quickly under which conditions the arm 125 is removed from locking engagement with the latch 123 and moves in under it, the parts impelled by the spring 121 and by the clutch springs 65 assuming the position shown in Fig. 11. In its movement from neutral to forward position the arm 114 turns the shaft 108 and the cams 107 and 113 acting on the levers 104 and 111 permit the drum 63 to be moved by spring pressure into frictional engagement with the drum 68 and leave the brake 76 in released condition. When in position of forward drive the lever 115 may be moved by reins 119 and 120 to operate the power steering mechanism to turn the tractor to the right or left in the same manner as when in neutral position. If the tractor is to be driven backward the operator pulls back on the reins under which conditions the arm 125 moves out from under the latch 123, the parts assuming the position shown in Fig. 10. In its movement to reverse position the arm 114 turns the shaft 108 in the reverse direction and the cams 107 and 113 acting on the levers 104 and 111 move said levers to move the drum 63 out of frictional engagement with the drum 68 and apply the brake 76. When in position of reverse drive the lever 115 may be moved by the reins 119 and 120 to operate the power steering mechanism to turn the tractor to the right or left as previously described.

The tractor is further provided with a drive pulley 141 mounted on the shaft 35 and with the shafts 34 and 35 thrown out of driving relation, the transmission means may be operated through the line drive control to connect the shaft 32 in driving relation with the shaft 35 to furnish power for driving other machinery.

In connection with the power operated steering mechanism means are provided for automatically moving the disks 96 to neutral position when the gear 80 is at the extreme positions of movement upon the rack 78. This means consists of an arm 142 secured to the steering shaft 130 and carrying adjustable screws 143 and 144 adapted to engage stops 145 and 146 respectively carried by the coupling 21. When the rear portion of the frame swings to the extreme left the screw 143 strikes the stop 145 and turns the shaft 130 to shift the member 99 to move the disks 96 to neutral position and when the rear portion of the frame swings to the extreme right the screw 144 strikes the stop 146 and turns the shaft 130 to shift the member 99 to move the disks 96 to neutral. When the disks 96 are in neutral position the gears 87 and 88 are loose on the

shaft 89 and the drive to the shaft 85 will be stopped.

Thus when the control for the driving mechanism is in neutral position, the steering mechanism may be operated to steer the vehicle to the right or left, when the control for the driving mechanism is moved forward the tractor moves forward and may be steered at the same time and when the control for the driving mechanism is moved backward the tractor moves backward and may be steered at the same time so that the steering mechanism is independent of the control for the driving mechanism though it may be operated at the same time.

I am aware that the details of construction herein shown and described are subject to some modification and change and I therefore desire it to be understood that such changes as come within the scope of the appended claims I deem to be within the spirit of my invention.

What I claim as my invention is:

1. In a control mechanism for tractors, the combination of a revoluble control shaft, a crank carried by said shaft, a lever centrally pivotally connected to said crank and provided with an arm extending outwardly from its central portion, a steering control member pivotally mounted on said control shaft, a link connecting said control member and the arm on said lever, said crank, lever arm, link and control member forming a parallelogram frame jointed at its ends, said lever being provided with laterally extending arms, and reins secured to the ends of said arms.

2. In a control mechanism for tractors, the combination of a revoluble control shaft, a crank carried by said shaft, a lever centrally pivotally connected to said crank and provided with an arm extending outwardly from its central portion, a steering control member pivotally mounted on said control shaft, a link connecting said control member to the arm on said lever, said crank, lever arm, link and control member forming a parallelogram frame jointed at its ends, said lever being provided with laterally extending arms, reins secured to the ends of said arms, a pull on the reins serving to move said frame to turn the shaft from "forward" to "neutral" or "reverse" position, means for moving said frame to move said shaft to "forward" position on a slackening of the reins, and means for releasably securing said frame and shaft in neutral position, said steering control member being operated through said frame by a pull on either rein.

3. In a tractor, the combination, with a source of power and a driven shaft, of a connection between said source of power and said shaft including a combined clutch and planetary gear transmission and a brake for securing the clutch in inoperative posi-

- tion when said planetary gears are operating, means for shifting the clutch into operative position, means for applying the brake, a revoluble control shaft operatively connected to said clutch shifting means and said brake applying means, and a line control device for operating said control shaft to operate said clutch shifting means and said brake applying means.
4. In a tractor, the combination, with a source of power and a driven shaft, of mechanism for connecting said driven shaft with said source of power for forward drive, mechanism for connecting said driven shaft with said source of power for reverse drive, cam operated means for controlling said forward drive mechanism, cam operated means for controlling said reverse drive mechanism, a cam shaft for actuating either of said cam operated means, steering mechanism including a steering control member, and means for connecting a pair of reins operatively to said cam shaft and steering control member for controlling the operation of said cam shaft by a pull on both reins and for controlling the operation of said steering control member by a pull on either rein said connecting means comprising elements pivotally connected together.
5. In a tractor, the combination, with a source of power and a driven shaft, of mechanism for connecting said driven shaft with said source of power for forward drive, mechanism for connecting said driven shaft with said source of power for reverse drive, cam operated means for controlling said forward drive mechanism, cam operated means for controlling said reverse drive mechanism, a cam shaft for actuating either of said cam operated means, steering mechanism driven by said source of power, and a line control device for controlling the operation of said cam shaft and said steering mechanism, said control device comprising elements pivotally connected together and

In testimony whereof, I affix my signature.

JAMES JESSEN.
